(57) **CLAIM**

The ornamental design for a drag chain kit, as shown and described.

DESCRIPTION

FIG. 1 is a perspective view of a drag chain kit, showing my new design;

FIG. 2 is a bottom plan view thereof;

FIG. 3 is a top plan view thereof;

FIG. 4 is a rear elevation view thereof;

FIG. 5 is a front elevation view thereof;

FIG. 6 is a left side elevation view thereof;

FIG. 7 is a right side elevation view thereof; and,

FIG. 8 is a further left side view thereof with an environmental structure shown in broken lines.

The dashed broken lines in the drawings illustrate portions of the drag chain kit that form no part of the claimed design. The dot-dash broken line showing of a truck is for the purpose of illustrating environmental structure and forms no part of the claimed design.
